UNITED STATES PATENT OFFICE.

GEORGE L. ROGERS, OF PHILADELPHIA, PENNSYLVANIA, ASSIGNOR TO HENRY DISSTON & SONS FILE COMPANY, OF PHILADELPHIA, PENNSYLVANIA, A CORPORATION OF PENNSYLVANIA.

BRUSH.

1,078,556.

Specification of Letters Patent. Patented Nov. 11, 1913.

Application filed June 12, 1913. Serial No. 773,323.

To all whom it may concern:

Be it known that I, GEORGE L. ROGERS, a citizen of the United States, residing in Philadelphia, Pennsylvania, have invented certain Improvements in Brushes, of which the following is a specification.

This invention relates to certain improvements in brushes used for cleaning files. A brush of this character has two varieties of bristles, one metallic and stiff and the other softer and flexible.

The object of this invention is to provide a spring handle which will hold the two elements to which the bristles are attached without other fastening means. These objects I attain in the following manner, reference being had to the accompanying drawings, in which:—

Figure 1, is a plan view of my improved brush; Fig. 2, is a side view; Fig. 3, is an end view, and Fig. 4, is a transverse sectional view of the handle on the line *a—a*, Fig. 1.

While the invention is particularly adapted for use in connection with a double brush for cleaning files, it will be understood that the invention can be used in connection with a single brush, or it can be used with a double brush differing in form and texture from that illustrated in the drawings.

Referring to the drawings, 1 is the handle made from a single sheet of steel bent into the shape shown and having two spring arms 2, 2 bent to form the grip section 3. The arms 2, 2 have inturned flanges 10 at the top and bottom, as illustrated in Fig. 3, and the grip portion is bent, as illustrated in Fig. 4, so as to make a convenient handhold and at the same time to strengthen this portion of the handle.

4 is a wooden block in which the flexible bristles 5 are secured.

6 is a strip of leather having the metallic bristles 7 bent as shown, and made similar to what is known in the textile industry as "card clothing."

The bristles 5 are made of any suitable material, preferably animal bristles, and are more flexible than the bristles 7. The bristles 7 are used to remove all hard particles

which accumulate in the ordinary metal file, and the bristles 5 are used to clean the file after the removal, by the other set of bristles, of the hard particles, as hereinbefore mentioned.

The block 4 and the leather strip 6 are placed back to back, as shown, and are not connected, so that when the bristles of either one of these sections wear the section containing them can be removed and another section inserted in the handle. The block 6 has a longitudinal groove 8 at each side, as shown in Fig. 3, into which extends one of the inturned flanges 10. The other flange of each arm engages the portion 9 of the leather strip 6 beyond the wire bristles 7 and indents the leather sufficiently to hold the elements 4 and 6 firmly in the handle. The handle is preferably made of spring metal so that, when it is bent into shape, as shown in Fig. 1, it has a tendency to grip the block 4 and to hold the block and the leather without the use of fastenings. Furthermore the inturned flanges grip the two elements so that they are held to the handle without other fastenings, which would be liable to become disarranged as the brushes of this character are roughly used and any intricate fastening device would be objectionable.

I claim:—

In a brush, the combination of a handle made from a single piece of sheet metal bent into shape to form a handhold and two spring arms, each of said arms having two inturned flanges bent so as to form a dovetailed groove in each arm; two brush blocks each having a longitudinal groove at each side, the arms being disconnected at the end opposite the handle so that the two blocks can be forced into the space between the two arms and the flanges entering the grooves in the blocks.

In testimony whereof, I have signed my name to this specification, in the presence of two subscribing witnesses.

GEORGE L. ROGERS.
